UNITED STATES PATENT OFFICE.

JACOB M. WEGMAN, OF PHILADELPHIA, PENNSYLVANIA.

BOX-MARKING MACHINE.

Application filed August 14, 1924. Serial No. 731,972.

My invention relates to a new and novel construction in machines for printing various markings and designations on the outside, particularly on the covers, of card board boxes such as are used for the merchandising of wearing apparel, for instance hosiery and underwear, and it relates more particularly to a novel construction in such machines, whereby the various designations, such as the size, style, color or lot number, as well as contents of the box, may be conveniently printed on the end or sides of the cover of the box without removing said cover from the box, and may be done so 15 with great rapidity and without any possible damage to the box or to the contents thereof.

My invention further relates to certain novel features of construction in such marking machines whereby the type for said marking may be changed quickly and without any great expense, so as to permit the efficient application of said machine to small as well as large lots of merchandise, 25 and it relates further to certain novel features of construction whereby said machine may be adjustable to fit any one of a number of shapes and sizes of boxes commonly employed in shipping merchandise of the 30 character described.

With the above ends in view, my invention consists of a certain novel adjustable multiple type holder carried by a type guide frame, having a parallel motion, governed by a certain parallel link support therefor, an adjustable printing table, and a revolving ink pad adapted to be fed automatically by the movement of the type frame.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Fig. 1 represents a perspective view of a construction in a box marking machine embodying my invention.

Fig. 2 represents a section on line 2—2 of Figure 3.

Fig. 3 represents an end view of my novel type holder.

Fig. 4 represents a section on line 4—4 of Figure 2.

Fig. 5 represents a plan view of my novel box marking machine.

Fig. 6 represents a section on line 6—6 of Figure 5.

Referring to the drawings, 1 designates the base of my novel box marking machine 65 preferably of cast iron, having the legs 2 as well as the side walls 3 integral therewith. The base 1 is preferably secured to the edge of a table or other support so as to position the same at a height convenient for operation. The type supporting frame 5 consisting of the two parallel guide rods 6 and the end plates 7, is pivotally secured to the ends of two parallel links 8 and 9 at each end of said type frame 5, the parallel links 75 8 and 9 being in turn pivoted to the side walls 3 of the base, at points 10 and 11 respectively, thereby confining the type supporting frame 5 to substantially parallel motion, between the two limiting positions 80 shown in Fig. 6. The operating handle 12, having the two arms 13, is pivoted at points 14 and 15, on the side walls 3, and on the end plates 7 respectively, thereby affording means to move the type supporting frame 5 85 from the ink pad 16 to the printing table 17 and back.

The type 18, necessary to produce the desired marking on the box 19, indicated in dotted lines in Fig. 1, and in full lines in 90 Fig. 6, is the conventional cast metal type, cast either as individual characters or as a complete line. The type holder 20 of my novel construction, consists of the steel frame 21 having a longitudinal parallel 95 guiding slot 22 therethrough, the spring backing 23 secured thereto permanently in any suitable manner, and having the rear spring prong 24 and the front spring 25 integral therewith. The spring backing 23 100 is provided with a longitudinal opening 26 therethrough, in alignment with the longitudinal opening 22 of the steel frame 21 of the type holder, said longitudinal opening 26 being sufficiently wide to receive within 105 it the threaded portions of the screws 27. The type 18 is held frictionally between the two parallel spring jaws 28 of the spring type clamps 29 shown in Figs. 2 to 4 inclusive. Each of the spring type clamps 110

29 is adapted to hold one line of characters to print one of the number of markings, such as the size, the color, or the style. Each of the spring type clamps 29 consists of a central base member 30 having a rectangular projection 31 integral therewith and adapted to be seated within the longitudinal parallel guide slot 22 of the steel frame 21 of the type holder 20, on to which base 21 10 30 are secured the spring jaws 28, by means of the rivets 32 or by any other convenient means, such as welding. Each of the central base members 30 are provided with a central, vertical threaded opening 33, into 15 which a screw 27 extends. The screw 27 passing through the slot or elongated opening 26 of the spring backing 23 into the threaded opening 33, secures the spring 20 type clamp 29 to the steel frame 21 of the type holder 20 rigidly, and in any position 25 along the length of said frame 21, into which it is set, so as to obtain any desired spacing between the successive lines of markings or designations. The rectangular projection 31 seated snugly within the parallel guide opening 22 aids in guiding the individual spring type clamps 29 parallel to each other, so as to print the successive lines of markings or designations in 30 parallel lines.

The characters having been properly positioned in each one of the spring type clamps 29, for the various markings, and the spring type clamps secured in the proper positions relative to each other on a type holder 20, said type holder is snapped on to the guide bars 6 of the type supporting frame, as shown in Figures 1, 2 and 6, by means of the spring prongs 24 and 25. The prong 40 24 is brought against one of the bars 6 and then the longer prong is snapped over the other bar 6. It will be noted that the type holder 20 may be attached at any point on the parallel bars 6 and a number of such type 45 holders 20 may be secured to the same type supporting frame 5, in a like manner, so as to produce a plurality of markings on the same line instead of being superimposed upon each other.

50 In order to permit the box 19 to be placed and positioned on the printing table 17, without opening the box or removing the cover, said printing table consists of a thin sheet of steel, as shown particularly in Fig. 55 6, having the front edge thereof bevelled upwardly as shown at 34 so as to permit said printing table 17 to slide freely between the inner and outer walls of the telescoping type of boxes in the closed position. The table 60 17 is preferably made in two or more panels as shown in Figure 5, each of said table panels being adjustably secured to the base 1 by means of the set screws 35 and the wing nuts 36, extending through a transverse

elongated opening 37 in the base 1, and a 65 longitudinal elongated opening 38 in the table panels 17, whereby each of said table panels 17 may be adjusted longitudinally and transversely so as to project out any 70 distance desired, and to provide for any width of box within the capacity of the machine. In order to provide added support for the thin printing table panels 17, against any flexure or deflection thereof under the 75 pressure of printing type, when said table panels are extended out a considerable distance, a supporting block 39 may be secured to the base 1 so as to form a continuous part thereof as shown in Figs. 1 and 6, by means of the tongue 40 and the groove 41 80 and the screw 42.

In order to guide the operator in positioning the box on the table 17 so as to print the markings opposite the proper designations, such as the size, style and color, I 85 provide the adjustable guides 43 secured to the table panels 17 by means of the set screws 44.

The ink pad 16 is carried on a steel disc 45 pivoted on the base 1, and adapted to 90 revolve about said pivot. The disc 45 is provided with a toothed periphery 47, whereby said disc 45, and said ink pad 16 are actuated periodically. The pawl 48 pivoted to the link 9 on the right side of the machine, is in operative alignment with the toothed periphery 47 of the disc 45 thereby revolving said disc a given distance, with every forward stroke of a handle 12 so as to change the position of the ink pad 16 with 100 every printing stroke.

It will now be apparent that I have devised a novel and useful construction in a box marking machine which embodies the features of advantage enumerated as desirable in the statement of the invention and the above description, and while I have, in the present instance, shown and described preferred embodiments thereof which will in practice give satisfactory and reliable results; it is to be understood that the same are susceptible of modification in various particulars without departing from the spirit or scope of the invention or sacrificing any of its advantages.

Having thus described my invention what I claim as new and desire to secure by Letters Patent, is:—

In a box marking machine, a base, a type supporting frame, a plurality of parallel links pivotally secured to said frame and said base respectively, a relatively thin printing table composed of a plurality of independent panels each adjustably and independently secured to said base and 120 extending beyond the same.

JACOB M. WEGMAN.
